UNITED STATES PATENT OFFICE.

JAMES A. EWING, OF SPRINGDALE, AND EDWARD J. McGOWAN, OF TARENTUM,
PENNSYLVANIA.

PLUMB-BOB.

1,349,565.

Specification of Letters Patent. Patented Aug. 17, 1920.

Application filed March 5, 1919. Serial No. 280,690.

To all whom it may concern:

Be it known that we, JAMES A. EWING and EDWARD J. McGOWAN, citizens of the United States, residing at Springdale and Tarentum, respectively, in the county of Allegheny and State of Pennsylvania, have invented certain new and useful Improvements in Plumb-Bobs; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an improved plumb-bob. The object being to provide an implement of this character that will afford a means whereby the plumb-line may be wound about a spring-actuated drum installed within the body of the plumb-bob, and automatically rewind the said line. A further object of the invention is to provide a means for adjusting the length of the plumb line and lock said line at any point along its length, and a further object is to adjust the several parts with relation to the plumb-bob proper, so that the point of the bob will maintain an accurate axial line with that of the plumb-line. With these and other objects in view, the invention consists in the details of construction and combination of parts, as will be fully described hereinafter.

In the accompanying drawings:

Figure 1 is a sectional side view, partly in outside elevation, of our improved plumb-bob, the same being constructed and arranged in accordance with our invention.

Fig. 2 is a side elevation, partly in section, the said section being taken at right-angles to that shown at Fig. 1.

Fig. 3 is a plan view having the top section removed.

Fig. 4 is a detailed sectional view of the winding drum or reel and its connected parts, showing the same detached from the body of the plumb-bob.

Fig. 5 is a side view of the same.

Fig. 6 is a view in perspective of the reel or drum shaft.

Fig. 7 is a face and outside view of the clamps which engage with the plumb-line, and

Fig. 8 is a face view and sectional elevation of the nut used for holding the clamps in position.

To put our invention in practical form, we first form the plumb-bob proper, in an upper 1, and lower section 2, the latter being fitted with the usual hardened conical point 3, attached by means of a threaded shank 4. These sections are connected, the one with the other, by means of a threaded flange 6, formed integral with the lower section 2, and a corresponding threaded socket formed with the upper section 1. Each of these two sections 1 and 2 is recessed at 5 and 5', in a manner that will admit the placing of a centrally-located, vertically-disposed, flanged winding reel or drum 8, about which the plumb-line 15, is wound. This drum 8, is mounted loosely upon a horizontally-arranged shaft 10, said shaft being formed with angular shouldered ends 11, which fit into notches 14, formed in the threaded flange 6, of the lower section 2, in such manner as to prevent said shaft from turning. Formed within the body of the drum 8, is a compartment, open at one side and said opening closed by a disk 9. This compartment contains a flat coil spring 12, one end 12', of which is attached to the inner periphery of the drum 8, and the other to the shaft 10, said shaft being slotted (17) a portion of its length, for the double purpose of said spring connection and as a spring frictional contact with the disk 9, as a means for holding said disk in position. The threaded flange 6, of the lower section 1, is recessed at diametrical points 7, located opposite the drum 8, (see Figs. 2 and 3,) thereby permitting the largest diameter drum to be used. The upper section 1, of the plumb-bob is formed with a contracted neck 19, provided with a screwthread for the purpose of attaching a screw cap 20, said cap being perforated to give the plumb-line 15, free passage therethrough, and an opening 21, formed vertically through said neck to the recess 5', of the upper section 1. The upper portion of the latter mentioned opening 21, is conical in form, the larger diameter at the top, and adapted to engage with two clamps; said clamps, when together, (see Fig. 7,) comprise a flanged portion 22, formed with integral conic frustums, the one 23, of greater diameter than the other 24, and each section of the clamp provided

- with a shallow groove 25. Arranged intermediate of the flanges 22, of the clamp and the mouth of the opening 21, is a threaded washer or nut 26, having wrench openings 28, said nut being provided with a central tapering opening of a greater diameter than that of the larger conic frustum 23. This nut 26, when in position, will prevent the displacement of the clamps, should screw cap 20, be disengaged from the neck of the plumb-bob. The upper section 1, of the plumb-bob and the screw cap 20, are each formed with serrated bands 16 and 16', to facilitate the separation of the parts.
- 15 The one end of the plumb-line 15, is attached to the drum 8, and the free end threaded through the opening 21, the clamp grooves 25, the nut 26 and screw cap 20. The tension is placed upon the coil spring by 20 winding the plumb-line 15, about the drum 8, placing the shaft in its bearings 14, and withdrawing the line, removing the drum from its bearings, care being taken to prevent the shaft 10, from turning, and the 25 line rewound upon the drum. This operation is repeated should more tension be desired.
- In operation. The screw cap 20, is loosened, thereby relieving the pressure of the 30 clamps upon the plumb-line 15. A predetermined length of the plumb-line is withdrawn from the drum, and the screw-clamp tightened downward upon the clamps, forcing their ends 24, against the conical walls of 35 the opening 21, thereby clamping the line 15, and holding the same rigid in this position. By releasing the screw-cap 20, the plumb-line will automatically rewind upon the drum 8.
- 40 It is obvious that slight changes may be made in the form of the clamps or other

details of construction, or that the holding washer or nut may be dispensed with, without departing from the spirit of the invention.

45

Having thus described our invention, we claim:—

1. A plumb-bob formed in two sections, the one attached to the other, said sections having a centrally-located recess formed 50 within the body of the same, and an axially-disposed opening having a conical-shaped mouth leading to said recess, a spring-actuated drum located within said recess, a stationary shaft carrying said drum, a coil 55 spring connecting said drum and stationary shaft, a plumb-line attached to and wound upon said drum, a screw-cap having a central perforation connected to the neck of the plumb-bob, a means comprising conical- 60 shaped clamps operated by said screw-cap, said clamps adapted to engage with the plumb-line and hold the same rigid at any point along its length and a means for confining said clamps in position.

2. A plumb-bob having a centrally-located recess, a spring-actuated winding drum arranged in said recess, a plumb-line attached to said drum, said recess having an axially-located opening leading therefrom, 70 a perforated screw-cap closing said opening, clamps engaging with said plumb-line and operated by the contact pressure of said screw-cap, and a means comprising a washer or nut for confining said clamps in position.

In testimony whereof, we affix our signatures in presence of two witnesses.

JAMES A. EWING,
EDWARD J. MCGOWAN.

Witnesses:

M. E. HARRISON,
HARRY C. WALLEY.
